UNITED STATES PATENT OFFICE

JACK MANOIL, OF BROOKLYN, NEW YORK

DESIGN FOR A CLOCK CASE

Application filed January 6, 1931. Serial No. 38,212. Term of patent 7 years.

To all whom it may concern:

Be it known that I, JACK MANOIL, a citizen of the United States, and residing at Brooklyn, in the county of Kings and State of New York, have invented a new, original, and ornamental Design for a Clock Case, of which the following is a specification, reference being had to the accompanying drawings, forming part hereof.

Fig. 1 is a face view, and Fig. 2 is a side view.

I claim:

The ornamental design for a clock case as shown.

JACK MANOIL.
